(57) **CLAIM**

The ornamental design for hand tool, as shown and described.

DESCRIPTION

FIG. 1 is a perspective view of a hand tool showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof; and,

FIG. 8 is the perspective view embodying the utilization of hand tool in which the broken line is for illustrative purposes only and forms no part of the claimed design.
